UNITED STATES PATENT OFFICE.

DE VER H. WARNER, OF BRIDGEPORT, CONNECTICUT, ASSIGNOR TO THE WARNER BROTHERS COMPANY, OF BRIDGEPORT, CONNECTICUT, A CORPORATION OF CONNECTICUT.

CORSET.

1,277,160.

Specification of Letters Patent. Patented Aug. 27, 1918.

Application filed June 14, 1916. Serial No. 103,672.

To all whom it may concern:

Be it known that I, DE VER H. WARNER, a citizen of the United States of America, and resident of Bridgeport, Fairfield county, State of Connecticut, have invented a new and useful Improvement in Corsets, of which the following is a specification.

My invention relates to an improvement in corsets and has particular reference to a 10 corset of the laced in front type. Heretofore, in corsets of this type it has not been thought possible to use clasps including steels or stiffeners tapering in width from the bottom upward, with the greater width at the bottom 15 because the construction of the laced in front corset would necessitate the locating of such clasp to one side of the middle of the front of the corset. As one of the purposes of such form of clasp is to give the greatest strength 20 where the greatest strain is, viz., over the abdomen, particularly in the case of corsets for stout wearers, such purpose would not be served by the placing of a broad ended steel or steels to one side of the said middle 25 line. By my invention I provide a corset wherein the utility of such broad ended steels is fully taken advantage of, resulting in a much stronger and more efficient structure of the type than heretofore. 30 In the following I have described, in connection with the accompanying drawing, a corset illustrating a way of practising my invention.

The drawing is a front elevation of a portion of a corset showing one embodiment of my invention.

In the form disclosed 1 indicates the body of the corset, provided at one side of the opening with a stiffening strip 2, a row of 35 eyelets 3 and a clasp member 4 of uniform width throughout its length. 5 indicates a clasp member adapted to coöperate with clasp member 4, the latter being provided with studs 7 to receive eyes 6 on clasp member 40 5. Clasp member 5 tapers outwardly from top to bottom being widest at the bottom. On the other side of the front opening is a stiffening strip 21, a row of eyelets 31, a straight sided boning steel 41 and a boning 45 steel 51 similar in shape to clasp member 5

and likewise tapering outwardly from top to bottom and being widest at the bottom.

8 indicates the lacing passed through eyelets 3 and 31 and adapted for adjustment of the corset to the wearer. The clasp members 55 4 and 5 are adapted for fastening the sides of the corset together when in position on the body of the wearer. Where the skirt 9 of the corset extends below the respective stiffening strip the eyelets 3 may be continued, hooks 10 and eyes 11 being provided on the extended portion to assist in fastening the corset.

It will be noted that the lacing 8 is in the middle of the front of the corset and that 65 the broad ended clasp member 5 and the broad ended boning member 51 are equi-distant from said middle line, the clasp member 4 and boning steel 41 also being in relatively similar positions on each side of said 70 middle line, so that the strain is evenly distributed on both sides and over the abdomen, the greatest strength being in the position of greatest strain.

It is thus seen that I have provided reinforcement of the corset at the point of greatest strain and have so balanced the reinforcing or stiffening strips that no undue thickness or bunchiness occurs at any point. Furthermore, the pressure upon the abdomen of the wearer is distributed over a comparatively large area and is not localized at one point or without pressure upon the abdomen at all, as heretofore in laced in front corsets. In fact I have produced a combined 80 abdominal support and laced in front corset. 85

It is obvious that the details of construction may be varied without departing from the spirit of my invention and I do not, therefore, restrict myself to such details further than the scope of the appended claim demands.

I claim.

A laced in front corset, having a lacing arranged in the middle of the divided front 95 of the corset, a broad ended clasp member and a similar broad ended boning member located on opposite sides of said lacing and equidistant from the middle line of the divided front, and a clasp member and a bon- 100

ing steel member also in relatively like positions on each side of said middle line, the combination and arrangement being such that the strains in use are evenly distributed on both sides and over the abdomen of the wearer, substantially as set forth.

In testimony whereof I have signed this
